UNITED STATES PATENT OFFICE

142,371

DESIGN FOR A WRIST WATCH

Ivan Bloch, Hartsdale, N. Y.

Application June 11, 1945, Serial No. 120,010

Term of patent 14 years

(Cl. D42—8)

To all whom it may concern:

Be it known that I, Ivan Bloch, a former citizen of Switzerland, having made application to become a citizen of the United States, residing at Hartsdale, in the county of Westchester and State of New York, have invented a new, original, and ornamental Design for a Wrist Watch, of which the following is a specification, reference being had to the accompanying drawing, forming part thereof.

In the drawing:

Fig. 1 is a front view of a wrist watch (with face closed) showing my new design;

Fig. 2 is a side view,

Fig. 3 is a top view, and

Fig. 4 is view similar to Fig. 1 (with face open).

I claim:

The ornamental design for a wrist watch, substantially as shown.

IVAN BLOCH.
